CARTON

Bernhard B. Sebreny, Chicago, Ill., assignor to
 Chicago Carton Company, Chicago, Ill., a corporation of Illinois

Application September 25, 1936, Serial No 102,493

5 Claims. (Cl. 229—17)

This invention relates to cartons and more especially to cartons which are intended for packaging of material in powder, granular, flake and other forms which may be poured from the carton 5 or container when opened.

The main objects of the invention are to provide an improved dispensing spout arrangement in a carton so as to facilitate the pouring of material from the carton, especially into small receptacles and in quantities to be measured. Other objects of the invention are to provide a dispensing spout arrangement in a carton, which may be formed in the carton without adding materially to the cost of producing the same carton 15 without the spout arrangement; to provide a spout arrangement which may be easily and repeatedly opened and closed; to provide a construction wherein the initial setting up of the spout is facilitated; and to provide a spout arrangement in which the parts when once set up 20 into spout form are effectively maintained in such form and in condition for instant use when desired.

In general it is the object of the invention to provide an improvement in cartons, especially in 25 respect of a dispensing spout arrangement therefor.

Other objects and advantages of the invention will be understood by reference to the following specification and the accompanying drawing 30 wherein there is illustrated a carton having a dispensing spout embodying a selective form of the invention. In the drawing—

Figure 1 is an illustration of a cardboard blank used for forming the carton;

Figure 2 is a perspective of the upper end portion of a carton showing the spout construction partially set up;

Figure 3 is a perspective similar to Figure 2, but showing the spout set up in its operative position; and

Figure 4 is a section on the plane indicated by the line 4—4 in Figure 3.

Referring now to the drawing, the carton or container may be formed from a suitable cardboard blank which is suitably creased or scored to divide the blank into a front wall portion 5, a back wall portion 6, and side walls 7 and 8 respectively. The walls 5, 6, 7, and 8 are adapted 50 to be folded relative to each other to form a rectangular container body, and a lip 9 is provided at one edge of the front wall 5 for adhesive attachment to the adjacent edge of the side wall 8 when folded to said rectangular form.

55 End flaps such as indicated at 10 are formed

on the bottom ends of the walls 5, 6, 7, and 8 and are adapted to be folded inwardly into overlapping relation, as indicated in Fig. 4, to form a bottom closure.

Similar end closure forming flaps are provided 5 on the upper ends of the walls 5, 6, 7, and 8, such flaps being respectively designated 11, 12, 13, and 14. As also indicated in Fig. 4, the flaps 11, 12, 13, and 14 are adapted to be folded into mutual overlapping relation to close the upper end of the 10 container. The various overlapping parts may, of course, be adhesively or otherwise united as is common in the art, and in accordance with the requirements of the purpose for which the container is designed.

In the upper end flap portion 11, provision is made by scoring as indicated at 15 and creasing as indicated at 16, for the formation of an opening by severing.

The generally rectangular portion 17, which is bounded by the scoring 15 and the creasing 16, is adapted to be severed from the surrounding flap portion 11 along the scored lines 15 and then bent upwardly along the creased lines 16. As indicated in Fig. 4, the flap 11 constitutes an 20 inner flap.

The flap 13, which constitutes an outer flap, is provided with scoring designated 18, with slits designated 19, and with creasing indicated at 20, joining the adjacent ends of the slits 19. As clearly shown, the slits 19 are so formed at their outer ends as to provide narrow end extensions designated 21, the purpose of which will presently appear. Creased or fold lines designated 22—22 are also formed in the portion of the outer flap which is surrounded by the scored, slit and creased lines 18, 19, and 20, said folded lines 22—22 serving to divide the surrounded portion into an intermediate portion 23 and end portions 24—24. For convenience said surrounded flap area may 30 35 40 hereinafter be referred to as a lip portion.

In setting up the container from the blank prepared as above explained, adhesive material may be applied to all or a part of the outside surface of the flap 11 or to the inside surface 45 of the flap 13, but provision is made to avoid the application of any adhesive to the inside faces of the end portions designated 24—24 and the front portion 25 of the intermediate portion 23. In Figure 1, the area in which adhesive is applied is indicated by the stippled shading. It will of course be understood by those skilled in the art that instead of applying adhesive to the limited area of the flap 13 as indicated in Fig. 1, the areas 24—24 and 25 may be treated with wax 50 55

or otherwise, and the outside surface of the flap 11 completely covered with adhesive. In such case adhesive would not adhere to the wax or otherwise treated areas 24-24 and 25 when the flaps are bent into contacting overlapping relation.

When the container is formed into the rectangular shape indicated in Figs. 2 and 3 with the flaps 11, 12, 13, and 14 folded into overlapping relation, the upper end of the container is normally flat. When it is desired to set up the spout structure to permit pouring of the content from the container, the outer flap portions 23, 24-24, and 25 are first separated from the surrounding flap portions along the scored lines 18-18 and the slit lines 19-19. This may be done conveniently by inserting the finger nail under the portion 25 intermediate the adjacent ends of the scored lines 18-18 which, as indicated in Fig. 1, are preferably arranged to terminate in spaced relation in the front or free edge 26 of the flap 13. By the application of a slight lifting force on the lip portion 25, the lip may be torn along the scored lines 18-18 from the surrounding flap portion until the lip is free to bend upwardly along the fold line 20. The position of the lip structure obtained by so separating it from the surrounding flap portion is indicated in Fig. 2. When the lip is so raised, the underlying rectangular portion 17 of the inner flap is incidentally separated along the scored line 15 from the surrounding inner flap portion and also caused to bend upwardly along the fold line 16.

It will be apparent that in the structure thus far described, the adhesively united lip portion 23 and inner flap portion 17 remain hingedly connected to the respective flaps of which they are a part. To facilitate simultaneous bending of the two portions 23 and 17 the fold or creased lines 16 may be multiplied to provide the necessary softness to permit sufficient stretching of the material of the inner flap in the hinge line to avoid the otherwise required relative movement between the portions 23 and 17 when simultaneously bent upwardly. Also if preferred, one of the parts, instead of being hingedly connected as at 16 or 20, may be completely slotted along said lines so as to provide freedom in the folding action of said parts. For practical purposes it is sufficient if either one of the folded flap parts remains hingedly connected to the flap part in which it is formed. For the purpose of this application it is assumed that double creasing or preliminarily stretching the fold line 16 provides satisfactory foldability of the two united flap parts.

When the parts have been adjusted to the position indicated in Fig. 2, the end portions 24-24 of the outer flap lip are folded forwardly towards each other until the extremities of their extensions 21-21 meet approximately centrally of the opening 17a in the inner flap, which opening results from the removal of the portion 17. The proportions of the flap part 17 and opening 17a are preferably so designed that when the end portions 24-24 are folded to a substantially parallel forwardly extending relation as indicated in Fig. 3, the extensions 21-21 will extend beyond the normal front edge 27 of the opening 17a. A bulge or notch designated 28 is formed in the front edge 27 of the opening 17a, the notch being spaced from the opposite sides 29-29 of the opening. The depth of the notch 28 is such that when the end portions 24-24 are bent to

such position that their outer extremities contact, they will pass freely through the notch portion 28 to the interior of the container. Thereupon the portions 24-24 are permitted to expand or spring outwardly until they are stopped by engagement with the side edges 29-29 of the opening 17a. In this position the side portions 24-24 cooperate with the inner flap portion 17 and the portions 23 and 25 to form a spout or chute which facilitates pouring of the container content into a small mouthed receptacle, spoon or any other article. When it is desired to close the container, the spout structure is merely pressed inwardly until the lip portion 25 engages the inner flap portion adjacent the front edge 27 of the opening 17a. Such engagement serves of course to limit the inward folding movement of the spout structure. Also re-opening is readily effected merely by again inserting the finger nail under the lip portion 25 and pulling upwardly. The end extensions 21-21 then engage the inside of the upper end closure of the container as illustrated in Fig. 4 to thereby limit the opening movement to a desirable operative position. The width of the flap portion 17 corresponds, of course, to the width of the opening 17a so that the side edges of the flap portion 17 normally engage the inner faces of the spout sides 24-24. Hence the flap portion 17 has a material tendency to urge the spout sides to swing outwardly and thereby effects substantial frictional contact between the outer faces of the spout sides and the respectively adjacent edges 29-29 of the opening 17a. Such frictional contact, in addition to the inherent tendency of the spout sides 24-24 to spring back to normal or initial co-planar relation to the spout portions 23-25, assists in maintaining the spout in desired opened or closed position.

It will be noted that by reason of the application of wax or other material to prevent adhesion between the lip portions 24-24 and 25 of the portions of the flap 11, the said portions 24-24 and 25 will freely separate from the said underlying portions when the spout structure is being set up as above explained. The accessibility of the front edge lip portion 25 constitutes an important feature in that it facilitates setting up and opening of the spout without the employment of a sharp edged knife or other instrument, the use of which, for the purpose of opening a container spout, is attended with some danger of accidentally cutting and destroying the container spout structure and also the person. By facilitating opening of the spout without requiring the use of a knife or the like, such attendant danger is eliminated and operability of the spout structure is substantially assured.

Changes in the described construction may be made without departing from the spirit of the invention, the scope of which should be determined by reference to the following claims, the same being construed as broadly as possible consistent with the state of the art.

I claim the following as my invention:

1. A container having an inner flap and an outer flap overlapping said inner flap and forming therewith a wall of the container, the outer flap being provided with a lip portion adapted to be separated from the flap along predetermined lines and bent to angular position relative to the flap along a predetermined line, end portions of said lip being foldable towards each other to form sides cooperating with an intermediate portion of the lip to form a spout, the inner flap being provided with a portion secured to said

intermediate lip portion and separable from the inner flap as an incident to bending of said lip to angular position, thereby to form an opening in said inner flap through which said folded lip 5 end portions are adapted to be projected into the container, whereby said spout is adapted to be repeatedly opened to form a dispensing spout and closed to close the container.

2. A container having an inner flap and an outer flap overlapping said inner flap and forming therewith a wall of the container, the outer flap being provided with a lip portion adapted to be separated from the flap along predetermined lines and bent to angular position relative to the flap along a predetermined line, end 10 portions of said lip being foldable towards each other to form sides cooperating with an intermediate portion of the lip to form a spout, the inner flap being provided with a portion secured 15 to said intermediate lip portion and separable from the inner flap as an incident to bending of said lip to angular position, thereby to form an opening in said inner flap through which said folded lip end portions are adapted to be projected into 20 the container, whereby said spout is adapted to be repeatedly opened to form a dispensing spout and closed to close the container, said lip portion extending to a free edge of said outer flap to provide an accessible edge portion facilitating 25 the initial separation and bending of the lip to form said spout.

3. A container having an inner flap and an outer flap overlapping said inner flap and forming therewith a wall of the container, the outer flap being provided with a lip portion adapted to be separated from the flap along predetermined lines and bent to angular position relative to the flap along a predetermined line, end 30 portions of said lip being foldable towards each other to form sides cooperating with an intermediate portion of the lip to form a spout, the inner flap being provided with a portion secured to said intermediate lip portion and separable from the inner flap as an incident to bending 35 of said lip to angular position, thereby to form an opening in said inner flap through which said folded lip end portions are adapted to be projected into the container, whereby said spout is adapted to be repeatedly opened to form a dispensing spout and closed to close the container, said inner flap portion being of such width as to normally engage said spout sides to urge the same to swing outwardly, thereby to maintain 40 frictional contact between the outer faces of said spout sides and the adjacent side edges of said opening.

so shaped as to provide a notch in one edge of the opening in said inner flap to facilitate initial insertion of said spout sides substantially as described.

4. A container having an inner flap and an outer flap overlapping said inner flap and forming therewith a wall of the container, the outer flap being provided with a lip portion adapted to be separated from the flap along predetermined lines and bent to angular position relative to the flap along a predetermined line, end portions of said lip being foldable towards each other to form sides cooperating with an intermediate portion of the lip to form a spout, the inner flap being provided with a portion secured to said intermediate lip portion and separable from the inner flap as an incident to bending of said lip to angular position, thereby to form an opening in said inner flap through which said folded lip end portions are adapted to be projected into the container, whereby said spout is adapted to be repeatedly opened to form a dispensing spout and closed to close the container, said lip portion extending to a free edge of said outer flap to provide an accessible edge portion facilitating the initial separation and bending of the lip to form said spout.

5. A container having an inner flap and an outer flap overlapping said inner flap and forming therewith a wall of the container, the outer flap being provided with a lip portion adapted to be separated from the flap along predetermined lines and bent to angular position relative to the flap along a predetermined line, end portions of said lip being foldable towards each other to form sides cooperating with an intermediate portion of the lip to form a spout, the inner flap being provided with a portion secured to said intermediate lip portion and separable from the inner flap as an incident to bending of said lip to angular position, thereby to form an opening in said inner flap through which said folded lip end portions are adapted to be projected into the container, whereby said spout is adapted to be repeatedly opened to form a dispensing spout and closed to close the container, said inner flap portion being of such width as to normally engage said spout sides to urge the same to swing outwardly, thereby to maintain frictional contact between the outer faces of said spout sides and the adjacent side edges of said opening.

BERNHARD B. SEBRENY.
